UNITED STATES PATENT OFFICE.

WILLIAM F. CASH, OF HIAWATHA, KANSAS.

MERRY-GO-ROUND.

No. 885,398.

Specification of Letters Patent.

Patented Nov. 6, 1896.

Application filed April 15, 1906. Serial No. 265,707.

To all whom it may concern:

Be it known that I, WILLIAM F. CASH, a citizen of the United States, residing at Hia-
watha, in the county of Brown and State of
Kansas, have invented new and useful Im-
provements in Merry-Go-Rounds, of which
the following is a specification.

This invention relates to merry-go-rounds
of the type which are manually operated, and
10 has for its objects to provide a simple and
comparatively inexpensive device of this
character which may be actuated by either
hand or foot power, which will run smoothly
and evenly, and one wherein reversed or ret-
rograde rotation is wholly obviated.

With these and other objects in view the
invention comprises the novel features of
construction and combination of parts more
fully hereinafter described.

20 In the accompanying drawings, Figure 1 is a
side elevation of a device embodying the
invention. Fig. 2 is a top plan view of the
same. Fig. 3 is a vertical sectional elevation,
on an enlarged scale, of the upper bearing.
25 Fig. 4 is a detail horizontal section of the
lower bearing. Fig. 5 is an enlarged detail
elevation of one of the clutch members. Fig.
6 is an enlarged sectional elevation taken on
the line 6-6 of Fig. 4.

30 Referring to the drawings, 1 designates a
vertical post or standard seated at its lower
end in a suitable step provided in a base 2
and having its upper end braced by means of
guys or braces 3, the standard being of circu-
35 lar form in cross-section and preferably tubu-
lar, as seen more clearly in Fig. 4. Fixed
upon the standard at a point adjacent its up-
per end by means of set-screws 4 is a bearing
member or head 5, having a raceway 6, in
40 which is arranged antifriction-balls 7, there
being arranged upon the standard and for
free rotation or travel upon the balls 7 a bear-
ing member 8, provided with a raceway 9, cor-
responding to the way 6 and having a hori-
45 zontal projecting portion or flange 10, perfor-
ated at suitable intervals, as at 11, for a pur-
pose which will hereinafter appear.

Fixed upon the standard 1 at a point above
and suitably remote from the base 2 is a hori-
50 zontal gear 12, while at a point beneath the
gear 12 there is fixed upon the standard a sec-
ond horizontal gear 13, there being arranged
between the gears and preferably adjacent to
the upper one a rotary bearing member or
55 sleeve 14, having journeled therein on verti-
cal axes a series of antifriction-rollers 15 con-

tacting with the standard 1. The bearing 14
carries a plurality, preferably four, hori-
zontal radiating arms or sockets 16, which re-
ceive the inner ends of the horizontal mem- 60
bers or beams 17, in turn equipped at their
outer ends with seats 18 and connected by
brace-rods 19 with the bearing member 8,
with which latter the rods are engaged
through the medium of hooks 20, entered 65
through the openings 11. It will be ob-
served from this construction that the entire
weight of the rotary frame comprising the
bearing 14 and arms 17 is sustained by the
upper bearing 8 and that free rotation of the 70
frame is insured by the provision of the anti-
friction-balls 7 and rollers 15.

Journaled in suitable hanger-bearings 21
on a pair of the beams 17 are operating-shafts
22, provided at their inner ends with pinions
23 in mesh with the gear 12, there being pro-
vided at the outer ends of the shafts 22 oper-
ating-crank 24, mounted loosely and each
carrying a clutch member or sleeve 25, hav-
ing teeth designed to mesh with a cooperat- 80
ing clutch member or sleeve 26 upon the
shaft and fixed for rotation therewith
through the medium of an engaging mem-
ber or pin 27, seated at the outer end of a
slot 28, extended longitudinally of the sleeve. 85
Mounted upon the shaft 22 is a normally ex-
panded spring 29, which bears at one end
against a stop or button 30 and at its other
end upon the inner end of the sleeve 26 and
serving to force the sleeve 26 normally into 90
engagement with the sleeve 25, thus opera-
tively locking the crank 24 to its shaft, as
will be readily understood.

Carried by and depending from the beams
17 are bearing members or hangers 31, in 95
which are journaled for rotation operating
members or shafts 32, each having at its inner
end a pinion 33 and at its outer end a crank
member 34 in the form of a foot-pedal, there
being formed upon each crank a clutch mem- 100
ber or sleeve 35 in toothed engagement with
a cooperating member or sleeve 36, slidably
disposed upon its shaft and having a slot 37
for the reception of a fastening member or
pin 38, while upon the shaft is a normally ex- 105
panded spring 39, which tends to maintain
the sleeve 37 in clutched engagement with
the member 35 in a manner similar to the cor-
responding parts above described.

In practice when the operating-shafts are
driven through the medium of the hand
cranks or pedals or both motion will be im-

parted to the frame through the medium of the pinions 23 33 and their respective gears 12 and 13, as general in devices of this character. In the event of the cranks being accidentally or intentionally turned backward the sleeves 26 and 37 will move inward upon their shafts in the direction indicated by the arrow in Fig. 5, thereby compressing the pressure-springs and throwing the cranks out of engagement with the shafts, thus preventing accidental retrograde rotation of the machine or injury to the latter, which might result through the intentional opposition of the strength of one of the occupants of the machine against that of another.

It is to be observed that the device herein disclosed is extremely strong and durable and that owing to the rotary frame being suspended from the bearing 8, which travels antifrictionally on the bearing 5, the movement of the device will be free and easy.

From the foregoing it is apparent that I produce a simple inexpensive device which will admirably perform its functions to the attainment of the ends in view, it being understood that minor changes in the details

herein set forth may be resorted to without departing from the spirit of the invention.

Having thus described the invention, what I claim is—

A merry-go-round comprising a shaft, a ball-bearing receptacle adjustably secured thereon, said receptacle being also provided with a surrounding rim-flange having perforations therein, gearings on the shaft arranged one above the other, a sleeve with sockets also arranged on the shaft, beams secured to the sockets having reversely-arranged hangers provided with bearings therein, brace-rods secured respectively at their opposite ends to the perforations of the flange and to the beams, and shafts rotatably mounted in the bearing of the hangers and having gears and operating means on their opposite ends, substantially as specified.

In testimony whereof I affix my signature in presence of two witnesses.

WILLIAM F. CASH.
